SINK MOUNTING TOOL

Harold K. Switzer, Trapp Court, Alexandria, Ky.
Filed June 27, 1958, Ser. No. 745,024
3 Claims. (Cl. 29—200)

This invention is directed to a tool for attaching lugs to a trim strip in order to mount a flat rim sink or laboratory bowl in a counter top. Lugs and a trim strip of the type for which the tool is designed are disclosed in my Patent No. 2,858,548, granted November 4, 1958.

As disclosed, the trim strip is substantially T-shaped in cross section to provide a head for spanning the opening between the rim of a sink bowl and the counter top to which the sink bowl is affixed, and a depending flange which extends down into the space between the sink and the counter top. The lugs are substantially L-shaped, providing a base leg which engages the underside of the counter top and an upright leg which engages the underside of the sink rim. The lug is secured to the vertical flange of the trim strip by deforming and clinching over a portion of the lower edge of the depending flange so that it hooks into a notch provided in the lug.

At the time the edge of the flange is being deformed and clinched over, it is necessary to apply a downward force on the flange to pull the head of the trim strip down tightly against the top of the drainboard and the sink rim, and at the same time apply an upward force upon the lug to engage it snugly against the underside of the drainboard and the sink rim. The holding force of the lug once it is in place is directly related to these forces applied by the tool at the time of installation. Hence, it is exceedingly important that these forces be applied in a positive manner and that the forces utilized on all lugs in an installation be identical so that rippling of the top of the sink trim strip is avoided.

The tool of this invention is designed with these things in mind, and it affords a means of rapidly and efficiently applying the lugs. Although the invention is disclosed in conjunction with a hand operated tool, it will be readily apparent to those skilled in the art that the tool may be powered by means such as compressed air, an electric motor, or hydraulic pressure, if desired.

In general, there are two methods commonly used in the assembly of a sink bowl, a trim strip, and a counter top. In one of the assemblies normally utilized in a manufacturer's plant the three components are placed upside down compared to their positions when installed in a kitchen. In this method the tool is used with the lug deforming and clinching head down. The second method is commonly used when the counter top is already in place in a kitchen and the sink bowl is to be installed. In this case the tool is used with the swaging head up. The tool operates equally well in either method, and it has the added advantage that in the second method it can be used easily in the small space available under the usual kitchen sink.

More specific objectives and advantages of the tool will be readily apparent to those skilled in the art from the following description of the drawings in which:

FIGURE 1 is a perspective view of the tool showing, the swaging head of the tool engaging a trim strip flange just prior to securing a lug in place;

FIGURE 2 is similar to FIGURE 1, but showing the top portion of the tool only as it would appear after securing the lug;

FIGURE 3 is a front elevational view of the tool on a smaller scale than in FIGURE 1;

FIGURE 4 is an enlarged cross-sectional, diagrammatic view taken along the line 4—4 of FIGURE 3, showing the pivotal path of the swaging beak of the tool through

2

the lug slot, permitting engagement with the trim strip flange;

FIGURE 5 is an enlarged cross-sectional view taken along line 5—5 of FIGURE 3 showing the tool ready for operation;

FIGURE 6 is similar to FIGURE 5, but showing the tool gripping the trim strip flange; and

FIGURE 7 is a fragmentary elevational view illustrating the relationship between the sink, swaged trim strip, and the connecting lug.

The action of the tool may be most simply described with reference to FIGURE 4. This view discloses a flat rim sink 1 mounted within an opening in a drainboard 2, and having a sink trim strip 3 of generally T-shaped configuration interposed between the sink and the drainboard. When utilized with the aforementioned assembly, said assembly being disclosed in my Patent No. 2,858,548, granted November 4, 1958, the present invention provides a quick and inexpensive means of mounting sinks by providing a means for simultaneously gripping and pulling downwardly on the depending vertical leg or flange 10 of the trim strip 3, supporting and forcing the connecting lug 4 upwardly, and deforming and clinching a part of the lower edge of the trim strip flange through the connecting lug slot 31.

FIGURE 1 discloses a preferred embodiment of the tool in which it can be seen that the tool may generally be described as comprising six parts: an elongated base member 5, a clevis assembly portion 6, an operating slide portion 7, a retaining jaw portion 8, a swaging beak portion 33, and an operating arm 9.

The generally rectangular base member 5, which serves only as a support for the tool, has an upper portion of rectangular configuration and a lower portion gradually tapered to form a smaller width at its lower end.

Retaining jaw portion 8 comprises two pairs of members being rigidly mounted on the face of the upper section of base member 5, namely, two rectangular vertical backing members 12 and two shoulder guide members 13. Vertical backing members 12 have beveled upper surfaces 14 to facilitate the guiding of the depending vertical leg 10 of trim strip 3 into operational slots 15. These operational slots are defined by the inner faces of the aforementioned backing members 12 and the opposite inner teeth of circular gripping teeth members 16. Shoulder guide members 13 are extended to form guide flanges 17 which extend outwardly from said shoulder guide members 13 being parallel to the faces of backing members 12. The inside faces of said guide flanges, together with the outside faces of shoulder guide members 13 and retaining springs 19 act as a guide for the two parallel, rectangular, slidably mounted operating rods 18.

When the tool is in the inactivated position, as disclosed in FIGURE 5, two activating screw members 48, one of which is horizontally threaded through each of the two guide flanges, engage their hardened, rounded tips 50 in activating notches 49 which are located in the face of each of the operating rods 18. As long as the tool remains in the inactivated position, retaining springs 19 press from their recesses 51 in the face of support member 5 and hold the operating rods 18 away from backing members 12 so as to engage their activating notches 49 with tips 50 and at the same time form operational slots 15 into which the lower leg of trim strip 3 depends.

As disclosed in FIGURE 6, when the operating rods are moved downwardly, tips 50 are cammed out of notches 49 and press against the faces of the operating rods, causing skirts 21 of the circular gripping teeth members fixed to the top portions of the rods to be moved inwardly and against the face of the depending leg 10 of the trim strip located in operational slots 15. As the operating rods are further moved downwardly, skirts 21

grip and bite into the depending trim strip leg, pulling downwardly and tightening the upper horizontal T portion of trim strip 3 flush against the upper surface of the sink and drainboard. The gripping skirts also hold the leg of the trim strip during the deforming and clinching process. Should notch 49 or tip 50 become worn or should there arise any other reason for adjusting the inwardly gripping movement of the gripping skirts, screw members 48 may be adjusted inwardly for this purpose.

Operating slide portion 7, among other elements, comprises parallel operating rods 18, the upper portion of each rod being capped with an aforementioned circular gripping teeth member 16. These circular gripping teeth members are formed of hard, circular caps, depending outwardly and downwardly from raised center portions 20 which are the heads of threaded screw members 23. The lower circumference of the caps form sharp-edged skirts 21, the lowest periphery of which form sharp, circular gripping edges, the circumference of these edges being greater than that of the largest circle that could be inscribed on the rectangular tops of the operating rods so that only a small arc of said circular gripping edge extends over the center of each edge of the top of the operating rods. To insure a larger gripping arc being exposed over the inner face of the operating rods, a recessed portion 22 is provided in the upper, inner faces of the operating rods. The gripping teeth members are mounted on the aforementioned operating rods by means of threaded screw members 23. The exposed screw heads 20 of screw members 23 provide a means for rotating the gripping cap so that when the exposed arcs over the inner, recessed faces of the operating rods become worn or damaged, the screw heads may be partially turned to present a fresh gripping arc for operational contact.

The main body of the operating slide portion is formed by the two operating rods 18; an upper 24 and lower 25 horizontal yoke; an operating bar 27; two equal sources of constant and predetermined spring force 26 being located on either side of the operating piston and between the upper and lower yokes; and two connecting shafts 28. As disclosed in FIGURE 5, connecting shafts 28 are circular and are slidably mounted through the upper yoke 24 to the bottom of the operating rods so that yoke 25 may slide downwardly along said shafts. The lower portions of connecting shafts 28 are fixed to lower yoke 25 by connecting nuts 29 which abut the lower face of lower yoke 25. The upper portion of operating bar 27 is enlarged to form a shoulder 30 which abuts the upper face of upper yoke 24 so that when the tool is in the inactivated position spring forces 26 press against the opposite inner faces of the two yokes holding the lower yoke 25 down against the shoulders 30 and 32 formed respectively by the enlarged upper portion of operating bar 27, and the lower portion of the rectangular operating rods 18.

The swaging beak portion 33 which is disclosed in FIGURE 4 is comprised of an operating strap 34; a pivotally mounted lever arm 35; and a deforming and clinching beak 38. The upper portion of operating strap 34 is eccentrically and pivotally mounted to the upper portion of lever arm 35 by connecting pin 36. Lever arm 35 is pivotally mounted on pivotal pin 37, between the inside faces of shoulder guide members 13. Operating strap 34 is fixed to the upper portion of the operating piston by means of operating pins 40. When the operating piston is moved downwardly, the attached operating strap acts to pivot the upper portion of lever arm 35 downwardly, at the same time pivoting the lower portion of said lever arm, from which deforming and clinching beak 38 protrudes upwardly. When depending leg 10 of the trim strip and connecting lug 4 are positioned as indicated in FIGURE 4, the aforementioned pivotal action will cause the deforming and clinching beak to pivot up through connecting lug slot 31, engage the lower portion of the depending trim strip leg and continue through the connecting lug slot, deforming and clinching the trim strip leg through the

upper portion of the connecting lug slot 31 as disclosed in FIGURE 7. It should be noticed that swaging beak 38 protrudes from lever arm 35 at a point just above the lower portion of the lever arm, leaving a shoulder 39, so that when it is desired to remove a connecting lug that has been swaged, the tool may be operated to an extreme position so that the swaging beak over-travels, causing shoulder 39 to follow the swaging beak through the upper portion of lug slot 31 and "wipe off" the deformed and clinched portion of the trim strip leg, releasing the lug.

Attention is directed to FIGURE 1 where clevis assembly portion 6 is disclosed as comprising a clevis 41, a pair of journal brackets 42, and a connector block 43. Journal brackets 42 are fixed onto base member 5 by means of journal bracket mounting pins 44, these brackets serve to pivotally mount the clevis between them on mounting pin 45. The lower portion of operating piston 27 is threaded into connector block 43 and pivotally joined to the clevis by means of clevis pin 46. Operating arm 9, equipped with handle 47, is mounted eccentrically and rigidly to the underside of the lower portion of the clevis. Operating piston 9 acts as a long moment arm, and when it is swung outwardly and upwardly away from base member 5, it pivots the lower portion of the clevis upwardly and outwardly with considerable force, at the same time pivoting the upper portion of the clevis inwardly and downwardly.

As the upper portion of the clevis moves downwardly, attached operating bar 27 is moved in the same direction. The downward motion of the operating piston initiates two other movements; operating strap 34 immediately begins pivoting deforming and clinching beak portion 33, and at the same time shoulder 32 on the operating piston abuts the upper face of upper yoke 24 and forces it to slide downwardly along connecting shafts 28 through lower yoke 25. The downward motion of the upper yoke causes spring forces 26 to be compressed between the downwardly moving upper yoke and the stationary lower yoke. Since lower yoke 25 is only slidably mounted to the operating piston and is fixed to operating rods 18, through connecting rods 28 and connecting nuts 29, it initially resists movement due to the fact that activating notches 49 in the operating rods are engaged with tips 50 of screw members 48. As the upper yoke proceeds downwardly, it increases the compression of spring forces 26 until such time as the force transmitted to the upper face of the lower yoke 25 by means of the spring forces exceeds the force tending to hold the lower yoke in a stationary position, at which time the lower yoke begins to move the operating rods downwardly.

As disclosed in FIGURE 6, when the operating rods are lowered, they are also cammed inwardly against the force of retaining springs 19 by the combined action of the tips of screw members 48 and activating notches 49. As the operating rods move inwardly and downwardly, gripping skirts 21 bite into the trim strip flange 10, pulling it downwardly and holding it firmly in the path of the pivoting deforming and clinching beak which operates between the two gripping skirts.

It should be remembered that equal spring forces 26 are of predetermined consequence, the summation of these forces being an equal and opposite force to the force actually exerted by the two gripping skirts against the trim strip flange. It should be emphasized that the continuous pivoting of the swaging beak commences immediately upon the downward movement of the operating piston while the gripping skirts are not actuated until the force exerted downwardly on the lower yoke exceeds the inertial forces acting on that same member. This important "lost motion" feature allows the same motivating component, namely the operating piston, to operate simultaneously both the deforming and clinching beak and the gripping skirts even though the action of the gripping skirts requires activation of a shorter duration than that required by the deforming and clinching beak.

When the operation of the tool is completed, the operating arm is swung back down to its original, inactivated position effectively pivoting the deforming and swaging beak back to its original posture and at the same time effectively raising the attached upper yoke 24, which in turn returns the operating rods to their inactivated positions. When upper yoke 24 is raised, the spring forces are relieved from the pressure formerly exerted by the aforementioned upper yoke and are free to expand.

In the particular embodiment of the invention disclosed in FIGURES 1 through 7, the tool is disclosed as being utilized in a situation where a sink is being installed in a mounted drainboard. This type of assembly requires that the tool be used under the drainboard in an "up-right" position, with the head of the tool at the upper end making operational contact with the work, and the operating arm and handle depending downwardly. The small size of the tool makes it particularly adoptable for this type of confined work.

Although not illustrated in the accompanying drawings, the tool is also adoptable to shoproom assembly wherein the sink and trim strip are placed upside down on the floor or other support member so that the opening of the sink is face down, and the drainboard is then laid around it. When the tool is used by a fabricator performing this type of operation, the tool is utilized in a position directly inverse to the one disclosed in FIGURE 1, that is, the head is now at the lower end, and the operating arm at the upper end. This type of assembly is preferred by most fabricators because visibility and working space are at optimum conditions; however, particular replacement situations and transportation requirements often dictate the use of the less popular method.

Having described my invention, I claim:

1. A tool for mounting a sink in an opening in a counter top by means of a trim strip and a plurality of mounting lugs, said trim strip being T-shaped in cross-section to provide a head to span the space between the rim of the sink and the counter top and to provide a vertical flange to depend into the space between the rim of the sink and the counter top, each of said lugs being L-shaped to provide a substantially horizontal leg to

engage the underside of the counter top and a substantially vertical leg to engage the underside of the sink rim, each of said legs having an apertured portion co-extensive with the juncture of said legs, said tool comprising:

- 5 prising a base member, means at the upper end of said base member defining a slot which is in a vertical plane extending transversely of said member, said slot adapted to receive said vertical trim strip flange, a beak, means pivotally mounting said beak adjacent to the upper end
10 of said base member, means for swinging said beak in an arc which is in a plane normal to the first named plane from a position at one side of the first named plane through said first named plane to a second position in which it projects beyond said first named plane,
15 the upper end of said base member including means to seat said lug with the aperture therein coextensive with the arc in which said beak is adapted to swing and with the vertical leg of the lug at the side of said slot at which the beak resides in its first named position whereby said
20 beak ruptures a portion of said flange and clinches said flange through the apertured portion of the vertical leg of said lug.

2. A tool according to claim 1, in which at least one wall of said slot is provided with means to removably grip and exert downward pressure upon said trim strip flange within said slot, said gripping means being operable upon the pivoting of said beak to firmly hold said flange in the path of said arc made by said beak.

3. A tool according to claim 1, in which said base member is elongated, said means for swinging said beak in an arc comprising; a clevis, a handle portion and an operating arm, means journaling said clevis for rotatable movement on said base member, said handle portion being fixed to said clevis to rotate said clevis, said operating arm having a lower end pivoted to said clevis, said operating arm having an upper end pivotally connected to said beak, said handle portion and said operating arm being parallel to said elongated base member.
